UNITED STATES PATENT OFFICE.

PHILLIP MOORE, OF PORTLAND, OREGON.

GANG AND SULKY PLOW.

SPECIFICATION forming part of Letters Patent No. 278,725, dated June 5, 1883.

Application filed June 22, 1882. (No model.)

To all whom it may concern:

Be it known that I, PHILLIP MOORE, a resident of the city of Portland, in the county of Multnomah and State of Oregon, have invented certain new and useful Improvements 5 in Gang and Sulky Plows, of which the following is a specification.

My invention relates to a sulky and gang plow in which the plows are located in front 10 of the sulky-wheels, and in which the means for either raising or lowering the plows out of or into the ground, as also the mechanism for regulating the depth of furrow, are located with reference to the driving-seat, so that the desired changes or movements can be made by 15 the driver from the seat; and the object of my invention is to construct a gang and sulky plow which will have direct draft, and in which the horses will be close to their work, 20 and to overcome the present defective means of lowering or raising the plows into or out of the ground, and provide therefor a simple, strong, and effective means of doing so; to arrange the mechanism for regulating the depth 25 of the furrow so that the same can be performed without taking apart any portion of the machine; and my invention consists in constructing and arranging the plows upon suitable beams in front of the sulky-wheels, close to 30 the team, by which arrangement a direct draft is obtained, so that no tongue is actually required; by constructing the standard of main plow in the form of a curved rack, with teeth extending above and below the beam, and located sufficiently close thereto and in position 35 to mesh in rack-teeth of a pivoted geared cam, to which is attached a hand-lever for operating with, by which the advantage is secured that the rack can run to the heel of the plow, 40 which can thus be lifted or lowered within greatly-increased limits, and having underneath the muzzle or end of plow-beam an adjustable caster-wheel, which performs the double function of steadyng the beam and that 45 of fulcrum when the plows are being lifted or lowered out of or into ground; by constructing the axle of sulky in two pieces, the main axle having a hollow elbow or standard, in which the furrow-wheel axle is fitted and adjusted 50 vertically by means of set-screws whenever the depth of furrow is changed.

In the accompanying drawings, forming part of this specification, Figure 1 is a view in perspective of my invention. Fig. 2 is a sectional view of the axles and the adjusting set-screws. 55 Fig. 3 is a view in section of the device for lowering and raising the plows.

A represents the axle of the sulky. This axle is constructed and arranged in two pieces, the main piece A having an elbow. 60

A' represents the elbow part thereof, which is hollow to receive the elbow-shaped axle B of the furrow-wheel. In the top of elbow A' is fitted a set-screw, b, there being a thread cut for set-screw in elbow A', which is for the purpose of setting the plows to the desired depth of work. b' is another set-screw in the side of elbow A', and is for the purpose of holding the axle B steady and firm in place. 65

C C' are the sulky-wheels, one on the land 70 and the other in the furrow.

D D' are the platform-braces, and are bolted to the back part of axle A and run back in a line with wheels C C'. To these platform-braces are attached the wheel cleaners or scrapers c c'. 75

E is the seat attached to the axle.

F F' are hounds bolted to axle A and elbow A', and they join together and form in front part of the muzzle of plow. Hound F is in a straight line with the furrow-wheel, and hound F' runs diagonal from axle A, near land-wheel C, to the muzzle of plow-beam. 80

e e' are braces for a foot-board and tool-box, one brace, e, being fastened to hound F', and 85 the other to cross-bar f of hounds.

G G' G' are flanges for the rack and cam arrangement of plows to work in. These flanges are attached to each other at l, and also to axle A and hound F, and to cross-bar f by bolts 90 and nuts.

H is a brace, which is attached to axle A, near the land-wheel C', and to flanges G' G'. This brace steadies and holds the plows in position. 95

I is the beam of main plow, having the curved standard J of plow made in one piece with it. The back of this curved standard J is constructed with rack-gear thereon, and is adapted to mesh with toothed cam K, whereby 100 the plows are raised or lowered. Cam K is pivoted in the flanges G G' in a slotted hole, g,

by a nut and bolt, *g*'. This slotted hole is for the purpose of allowing the cam *K* to be thrown out of gear with standard *J* by loosening the nut. It can be pushed back out of gear. The 5 upper part of cam *K* terminates in a stub or handle, *k*, upon which is fitted lever *j* by bolt and nut *j*'.

L L' are the plows, of usual style, and having standing cutters *l l'*.

10 *M* is the beam of outside or wing plow, being attached to beam *I* and a brace, *m*, and bolts and nuts *m*'. The front ends of both beams *I* and *M*, in conjunction with three muzzle-pieces, *d d d*, form the muzzle of the plow, 15 to which is attached the clevis *i* by pin' and key *e*'. Beam *M* has a recess formed on inner side, where it fits against beam *I*, into which fits the pendent hinges *N*, and on the outside of beam *I* the other pendent hinge *N* fits, two 20 bolts and nuts, *n n*', holding them together. These hinges *N N'* are fastened above between the hounds *F F'* by bolts and nuts *h h*, the arrangement of ends of beams *I* and *M* allowing oscillation, in conjunction with hinges *N N'* 25 and bolts *n n*', when the plows are raised or lowered.

Upon outside of hound *F* is attached an ear, *O*, in which the shaft of a caster-wheel, *P*, is fitted. This caster-wheel is adjustable upon 30 its shaft by means of a set-screw.

Q is a brace running from axle *A* to muzzle of plow, being provided with a swivel or tightening joint, *p*.

R is the socket for the tongue, if one is used; 35 being on top of hound ends.

S is the notched rack, in which the lever is rested when raising or lowering the plows. This rack is fastened to the hound cross-bar *f* and platform by bolt and nut.

40 The following is the operation of my invention: When it is desired to adjust the plows to work deeper or shallow, the set-screw *b*' is loosened and the set-screw *b* is turned until the desired depth of furrow is attained. Then the 45 set-screw *b*' is tightened up again and the plow is ready to run. And when it is necessary to lift the plows out of the ground, either to avoid some obstruction in the land or to move to another field, then the driver raises, by pulling 50 upon the lever, the standard *J* and plows by means of the cam *K*, and when the plows are

raised high enough then the lever can be rested in a notch in rack *S* and the plow driven anywhere. The tongue can be removed when desired by simply drawing a pin out of the 55 socket. In plowing it is not necessary to use any tongue, as the construction and arrangement of my plows in front of the wheels, and the location of the plow-beams and hounds, make the draft direct; but in moving about 60 from field to field the tongue may be necessary.

I am aware that jointed axles have been made consisting of a hollow sleeve forming part of one axle, and an elbow forming part of another axle fitting therein, in which the movement of the elbow in the sleeve is regulated by a lever and link, as in the patent to G. A. Davison, No. 79,639, granted July 7, 1868, and reissued October 12, 1869, as No. 3,669; also, that jointed axles have been made in which 70 a block carrying one axle-arm is adjusted up and down a slot in a downwardly-projecting standard by an adjusting-screw, as in the patent to F. Girtanner, No. 236,574, granted January 11, 1881. 75

I am further aware that plow-beams having toothed standards have been raised and lowered by a cam and lever, but without the use of flanges or guides. Such a plow is described in patent to J. and J. Ingham, No. 80 65,087, granted May 28, 1867.

Having described my invention, what I claim as new, and desire to secure by Letters Patent, is—

1. In a gang and sulky plow, the axle *A*, 85 having the hollow sleeve *A*', made in one piece, in combination with elbow-axle *B*, adjusting-screw *b*, working through the top of the sleeve, set-screw *b*', and wheels *C C'*, operating as shown, and for the purpose set forth. 90

2. The combination, in a gang and sulky plow, of the plow-beam *I*, the standard *J*, having the curved rack thereon, extending above and below the beam, and the plow secured to the standard, with suitable gearing for lifting and lowering the plows, substantially as hereinbefore set forth. 95

PHILLIP MOORE.
